[57] CLAIM

The ornamental design for a faucet, as shown and described.

DESCRIPTION

FIG. 1 is a front perspective view of a faucet showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof, with the spout rotated 180 degrees; and

FIG. 7 is a right side elevational view of FIG. 6.

The broken line representation of an escutcheon in FIG. 1 and an aerator in FIG. 3 are for purposes of illustration only and form no part of the claimed design.
